The ornamental design for a JET REGULATOR as shown and described.

DESCRIPTION

FIG. 1 is a front elevational view of a first embodiment of a JET REGULATOR in accordance with our design;
FIG. 2 is a right side elevational view thereof;
FIG. 3 is a top plan view thereof;
FIG. 4 is a top, front, right perspective view thereof;
FIG. 5 is a bottom plan view thereof; and
FIG. 6 is a bottom, left, rear perspective view thereof;
FIG. 7 is a front elevational view of a second embodiment of a JET REGULATOR in accordance with our design;
FIG. 8 is a right side elevational view thereof;
FIG. 9 is a top plan view thereof;
FIG. 10 is a top, front, right perspective view thereof;
FIG. 11 is a bottom plan view thereof; and
FIG. 12 is a bottom, left, rear perspective view thereof;
The angled line shading in FIGS. 9 and 10 represents the color green;
FIG. 13 is a front elevational view of a third embodiment of a JET REGULATOR in accordance with our design;
FIG. 14 is a right side elevational view thereof;
FIG. 15 is a top plan view thereof;
FIG. 16 is a top, front, right perspective view thereof;
FIG. 17 is a bottom plan view thereof; and
FIG. 18 is a bottom, left, rear perspective view thereof;
The stippled shading in FIGS. 15 and 16 represent a contrast in appearance only and does not represent any particular color, material, texture, or finish. Additionally, the broken lines represent portions of the JET REGULATOR that form no part of the claimed design.
